UNITED STATES PATENT OFFICE.

JOHN I. LEFORS, OF BOISE, IDAHO.

AMALGAMATOR.

1,260,781.

Specification of Letters Patent. Patented Mar. 26, 1918.

Application filed March 4, 1916. Serial No. 82,170.

To all whom it may concern:

Be it known that I, JOHN I. LEFORS, a citizen of the United States, and a resident of Boise, in the county of Ada and State 5 of Idaho, have invented a certain new and useful Improvement in Amalgamators, of which the following is a specification.

My present invention relates generally to machines for the purpose of handling placer 10 gravel and saving the fine gold contained therein which is ordinarily lost in the machines and apparatus for this purpose now in use, and more particularly to an amalgamating apparatus acting upon the gold contained material in successive operations, my 15 object being to provide an apparatus of this type which will actually and effectively save the fine gold or "flour" gold, and also concentrate any other metal or mineral that may 20 be contained in black sand or gravel content in alluvial or placer mining ground.

In the accompanying drawings in which I have illustrated the preferred embodiment 25 of my invention, and which form a part of this specification:

Figure 1 is a side elevation illustrating the practical application of the complete device.

Fig. 2 is a vertical cross section through the amalgamator taken substantially on line 30 3—3 of Fig. 1.

Fig. 3 is a detail plan view of the amalgamator bed.

Fig. 4 is a detail section through the amalgamator bed, taken substantially on line 5—5 35 of Fig. 3.

Referring now to these figures, and particularly to Fig. 1, the gravel or material to be acted upon is dumped into an intake flume 10 leading to the set of grizzly bars indicated 40 in this figure generally at 11. Waste material from the grizzly bars 11 finds its way into the waste flume, seen at 14, down which it is carried and from which it is discharged.

The grizzly bars 11 are disposed at the 45 lower end of the intake flume 10 above a tank 15 as seen in Fig. 1, and between the grizzly bars and the tank 15 is disposed a boxed-in screen 16 which catches the material falling through the grizzly bars, the 50 material incapable of passing through the screen being moved downwardly thereover and into the waste flume 14 which receives the material from the grizzly bars.

The material passing downwardly through 55 the screen 16 falls into the before mentioned tank 15, the latter of which is tapering, and

communicates with the upper end of a laterally extending and downwardly inclined feed chute 21, leading to the stationary classifier 22 at a point adjacent one side of its rear 60 or upper end, the classifier 22 consisting of a plate inclined slightly in a downward direction toward its forward end where it communicates with a waste flume 23.

This classifier 22 just mentioned is provided with a series of riffles 24 arranged at a desired angle, forming between them inclined channels for the reception and transportation of the heavy material content, all material of a lighter specific gravity than 70 gold, black sand, platinum, being washed into the waste flume 23, the other heavy material contents drop into the channels between the riffles 24 and are carried thereby laterally at an angle to one side and onto a 75 feed board 27 extending laterally from the classifier and of gradually decreasing width toward its outer end.

The feed board 27 just mentioned is provided with a plurality of converging grooves 80 28 insuring equal distribution of the material flowing over it, and an even discharge of the material from its outer end onto the amalgamator.

The amalgamator as best seen in Fig. 1 85 has an inclined bed 29, the inclination of which is in a longitudinal direction, which is given a shaking or vanner motion through connections 30, for this purpose, from a driven shaft 31 below and at one side of 90 the bed, the bed, through vertical supports 32, supporting a pair of spaced parallel troughs 33 longitudinally thereabove, and inclined in the direction of their length and in a direction opposite to the inclination 95 of the bed 29 as will be particularly seen by reference to Fig. 1.

Centrally located above and longitudinally extending along each of the troughs 100 33 is one of a pair of lower copper plates 34, horizontally aligned and thus spaced a considerable distance apart, the said plates thus located being detachably connected to the intermediate portions of the supporting uprights 32 with their centers below the 105 longitudinal side edges of the upper copper plate 35 which latter is also detachably connected to the supporting uprights 32 with its center below the outer edge of the feed board 27.

Thus, material from the feed board 110 strikes the center of the upper copper plate

35 and the overflow from the lateral edges of this plate drops upon the lower plate 34, and from the latter to the trough 33, moving downwardly and rearwardly in the latter and from its lower end onto the upper rear end of the bed 29.

The upper sections of the bed 29, as particularly seen in Fig. 3, upon opposite sides of its central longitudinal dividing partition 36, are provided with a plurality of cups 37 which, with the riffles 38 in the lower part thereof, concentrate all the material that passes from the amalgamator plates 34 and 35, the cups 37 holding 10 the heavier concentrates, and the lighter concentrates passing on into the riffles according to their relative specific gravity, until all light material or waste is washed out over the tailing board 39 at the lower 15 forward ends of the bed, as seen in Fig. 1.

Thus, by means of the successive apparatus, the construction and operation of which have now been described, I am enabled to effectively save the fine or flour 20 gold, the greater proportion of which goes to waste in the ordinary construction of placer mining machines.

I claim:—

1. An amalgamator comprising an upper 30 central amalgamating plate onto which the material is delivered, lower amalgamating plates arranged in spaced relation below the side edges of the upper central plate to receive material from the latter, and troughs 35 arranged below the lower side amalgamating plates for discharging the material therefrom.

2. In a placer mining machine, an amalgamator including an upper amalgamating 40 plate onto which the material is fed, lower

amalgamating plates arranged below the side edges of the said upper plate, troughs inclined below said lower plate, and a concentrating bed to which the said plates and troughs are connected inclined in a direction opposite to that of said troughs and onto the upper end of which the lower ends of the said troughs discharge and means for vibrating the bed and plates as a unit. 45

3. In a mining machine, an amalgamator 50 including a lower vibratory concentrating bed, upper amalgamating plates connected to and vibrating with the concentrating bed and arranged to successively receive and act upon the ore-bearing material, and troughs 55 inclined beneath the amalgamating plates and between the same and the concentrating bed, said troughs being inclined lengthwise of the concentrating bed to discharge the material after passage over the amalgamating plates onto one end of the concentrating bed. 60

4. In a mining machine, an amalgamator including a lower vibratory concentrating bed, upper amalgamating plates connected to and vibrating with the concentrating bed and arranged to successively receive and act upon the ore-bearing material, and troughs 65 being inclined beneath the amalgamating plates and between the same and the concentrating bed, said troughs being inclined lengthwise of the concentrating bed to discharge the material after passage over the amalgamating plates onto one end of the concentrating bed 70 75 being inclined in a direction opposite to the inclination of the troughs, for the purpose described.

JOHN I. LEFORS.
